DESIGN FOR A BATHING SUIT

Rose Marie Reid, Los Angeles, Calif.

Application October 10, 1946, Serial No. 133,867

Term of patent 7 years

(Cl. D3—17)

To all whom it may concern:

Be it known that I, Rose Marie Reid, a citizen of the United States, residing at Los Angeles, in the county of Los Angeles and State of California, have invented a new, original, and ornamental Design for a Bathing Suit, of which the following is a specification, reference being had to the accompanying drawing, forming part thereof.

Fig. 1 is a front view;

Fig. 2 is a rear view; and

Fig. 3 is a side view of a bathing suit, showing my new design.

I claim:

The ornamental design for a bathing suit, as shown.

ROSE MARIE REID,
